(57) **CLAIM**

The ornamental design for a lanyard, as shown and described.

DESCRIPTION

FIG. 1 is a top perspective view of the lanyard showing my new design;

FIG. 2 is a front elevational view thereof, with the rear view being identical;

FIG. 3 is a left side elevational view thereof, with the right side elevational view being identical; and,

FIG. 4 is a bottom plan view thereof.

The broken line showing of a lanyard in FIGS. 1–4 is for illustrative purposes only and forms no part of the claimed design.
